UNITED STATES PATENT OFFICE.

LÉON EMILE RÉMONDY, OF PARIS, FRANCE.

PROJECTILE FUSE.

Application filed February 5, 1927, Serial No. 166,237, and in France May 6, 1926.

The present invention relates to percussion fuses for projectiles or bombs.

The fuse according to the invention only comprises in addition to the usual members 5 of the firing mechanism (percussion cap and striker), two compressible supports; it requires no safety member although its operation cannot take place in the bore of the gun barrel or in the event of a fall of the projectile from a small height; and finally, the 10 elements of the fuse (percussion cap, striker and compressible supports) are adapted to be placed in position directly in the lodgment provided for them in the fuse body. 15 The fuse according to the invention is essentially characterized by the feature that the rear element of the firing mechanism (preferably the percussion cap or primer) is placed between two elastic supports of 20 different degree of compressibility, the rear elastic support, of greater compressibility, resting upon the base of the lodgment provided in the fuse body, while the front support of smaller compressibility abuts at the 25 front end against the complementary member of the mechanism (preferably the striker) which is prevented from escaping outwardly relative to the fuse body by a shoulder formed upon said fuse body, said 30 complementary member being free to make an inward movement over a limited distance determined by another stop also formed upon the fuse body.

The invention is capable of receiving a 35 variety of mechanical expressions, several of which are shown on the accompanying drawings, but it is to be expressly understood that the drawings are for purposes of illustration only and are not to be construed as a definition of the limits of the invention, reference being had to the appended claims for that purpose. Referring in detail to the drawings, wherein like reference characters are employed to designate similar parts 40 in the several views—

Fig. 1 is an axial sectional view of an embodiment of the present invention; and

Figs. 2, 3, 4, 5 and 6 are similar views of other embodiments of the invention.

50 In the form shown in Fig. 1.

The elastic supports of different degrees of compressibility are formed by springs. In this figure, A is a fuse body in which a lodgment A¹ is provided for the whole of 55 the firing mechanism, which lodgment com-

municates with the detonator through a duct A².

According to the invention one of the two elements of the mechanism, preferably the percussion cap B, is placed between two 60 elastic supports C and D of different degrees of compressibility, formed in this case by helical springs.

The rear elastic support C, of greater compressibility, rests, at its back end c, upon 65 the base a of the lodgment A¹ provided in the fuse body A. The front elastic support D, of smaller compressibility than C, bears at its front end against the head K¹ of the striker E. The latter is prevented from 70 making any outward movement by a shoulder a¹ formed upon the fuse body, for example, by turning in the outer lip or edge of the latter.

The striker is adapted to make an inward 75 movement over a small distance, after which it abuts against a shoulder a² also formed upon the fuse body A. The difference in compressibility between the two springs C and D may be obtained by a difference in 80 section of the material composing the springs; the springs may also be of the same kind and the spring C made longer than the spring D.

When an obstacle is struck, even a very 85 light one, such as the wing fabric of an aeroplane, for example, the fuse operates instantaneously. In fact, the striker K, which may be very light, is driven into the fuse body until it abuts against the shoulder a² 90 and this movement takes place while the fuse body A and the projectile, penetrating into the very light obstacle or pushing the latter back, continue their forward movement at the only slightly reduced speed of 95 the projectile at that moment. The percussion cap B the kinetic energy $1/2 m V^2$, of which is very high on account of the very high value of the factor V^2 (where V is the residual speed of the projectile), compresses 100 the spring D and strikes the point of the striker K.

On the other hand, in the event of a fall of the projectile from a small height, even on to a hard body the striker is driven back 105 as far as the shoulder a² but cannot reach the percussion cap B which is itself driven back a corresponding distance by the spring or elastic support D. The latter offers a greater resistance than the spring or support 110

C and since the kinetic energy of the percussion cap is, under these conditions very small, said cap cannot materially assist in compressing the spring or support D.

5 When a projectile fitted with the fuse of the present invention is fired from a gun, the force of "set-back" is ineffective to produce impact between the striker and percussion cap, since spring C is more readily compressible than spring D, and preferably the mass of the percussion cap is greater than the mass of the striker K. Set-back therefore increases the distance between the percussion cap and striker.

10 In the example described above the springs having different degrees of compressibility may naturally be considerably varied in shape. They may be replaced by Belleville rings or by elastic bellows made of metal, 20 metal and leather or any other suitable bellows.

In the form shown in Fig. 2 the elastic supports having different degrees of compressibility, between which the percussion 25 cap is placed, are formed by sleeves made of a plastic material such as cork, for example, or felt.

The difference in compressibility may be obtained by a simple difference in height of 30 the compressible members. The sleeve D¹ which forms the upper compressible support may be so constructed that the axial duct passing through it serves as a guide for the pin E of the striker E—E¹.

35 The elements of the fuse, instead of being disposed entirely and directly in a lodgment provided in the fuse body A may be completely or partly lodged in a socket or gaine F, at the bottom of which socket is 40 housed and secured a detonating percussion cap G. Finally, the whole arrangement formed by the striker E—E¹, the percussion cap B and the two supports C¹, D¹ of different degrees of compressibility, may, as 45 shown in Fig. 3, be disposed in a socket or gaine H which is a simple sleeve fit in the lodgment provided for it in the fuse body A. The lower part of this socket may constitute a support for the detonating percussion cap G. Strips H¹ may be cut in the wall of the 50 socket H and turned inwards so as to form stops preventing any forward movement of the percussion cap B.

55 As shown in Figure 4 the socket or sleeve containing the whole of the fuse and detonating percussion cap may be formed by the fuse body itself which will be suitably shaped for this purpose.

60 Figure 5 shows an embodiment of the invention in which the sleeve H¹ containing the whole of the mechanism (E—B—C¹—D¹) and the detonating percussion cap (G) is provided with screw threads h for screwing the fuse into the projectile.

65 Figure 6 shows an embodiment of the in-

vention in which the elastic supports are, as in the embodiments shown in Figures 2 to 5, formed by sleeves made of a plastic material. In this case any forward movement of the percussion cap B is prevented by the 70 end face of a sleeve I which is itself held in place by its flange or collar i which is gripped between one of the elements A of the fuse body and a front removable element A^x screwed upon A, upon which element 75 A^x are formed the abutment shoulders a¹ which prevent the outward movement of the striker.

Naturally, the principle of construction according to which the whole of the firing 80 mechanism and detonating percussion cap is located in a common sleeve or socket which may be formed by the fuse body itself is adapted for use whatever be the mode of construction of the percussion mechanism. 85 The striker may comprise a portion of reduced diameter e which in the case of a graze or angle impact will permit the head E¹ of the striker to be deformed without deflecting the point E from its original direction. 90

Having now particularly described and ascertained the nature of my said invention and in what manner the same is to be performed, I declare that what I claim is:

1. A fuse comprising a fuse body having 95 formed therein a gaine, primer and striker elements positioned in said gaine, an elastic support intermediate said elements, and an elastic support intermediate the rearwardly positioned one of said elements and 100 the bottom of said gaine, the last mentioned one of said supports being more yielding than the first mentioned support.

2. A device comprising a fuse body having 105 a recess formed therein, primer and striker elements arranged in series in said recess, means for limiting the movement of one of said elements, a yielding support intermediate said primer and striker elements, and a yielding support positioned intermediate the fuse body and the rearwardly mounted one of said elements, said second named yielding support being more readily yieldable than the first named yielding support. 110

3. In a device, a fuse body having a recess therein, primer and striker elements positioned in alignment in said recess, a yielding support intermediate said primer and striker elements, and a yielding member 120 having direct engagement with said primer and said fuse body, said primer and striker being relatively and longitudinally slidable at all times in said recess.

4. In a device of the class described, a 125 fuse body having a recess therein, a sleeve fixedly positioned in said recess, primer and striker elements slidably mounted in said sleeve, yielding means only for resisting relative movement between the primer, striker 130

and fuse body, one portion of said means being more yielding than another portion thereof, and a detonating percussion cap carried by said sleeve.

5 5. In a device of the class described, a fuse body, a striker having an enlarged head slidably mounted within the fuse body adjacent the forward end thereof, a primer slidably mounted in said fuse body in alinement with said striker, yielding means operatively engaging said primer and striker, and yielding means of greater compressibility than said first named yielding means interposed between said primer and fuse body.

10 6. In a device of the class described, a fuse body, primer and striker elements slidably mounted in alinement, in said body, said body being provided with means for 20 positively limiting movement of one of said elements, and yielding means engaging the opposite faces of the other of said elements to resist engagement of said elements.

15 7. In a device of the class described, a fuse body, primer and striker elements slidably mounted, in alinement, in said fuse body, and tubular yielding members interposed between said elements and between one of said elements and the fuse body, the

last named tubular member being more 30 yielding than the tubular member interposed between said elements.

8. In a device of the class described, a fuse body having a recess therein, primer and striker elements slidably mounted, in 35 alinement, in said recess, a tubular yielding member interposed between said primer and striker, and a tubular yielding member interposed between said primer and said fuse body, the last named tubular member being 40 more yieldable than the first named tubular member.

9. In a device of the class described, a fuse body having a recess formed therein and a shoulder provided adjacent one end 45 of said recess, a striker slidably mounted in said recess and normally having engagement with said shoulder, a primer slidably mounted in said recess, yielding means interposed between said primer and striker, 50 and yielding means interposed between the striker and fuse body, said last named means being more yieldable than the first named yielding means.

In testimony whereof I have signed this 55 specification.

LÉON EMILE RÉMONDY.
